BAG DISPENSING CONTAINER
Emanuel Kugler, 124 Richmond Place, Lawrence,
Long Island, N.Y.
Filed Aug. 10, 1965, Ser. No. 478,671
3 Claims. (Cl. 229—51)

This invention is concerned generally with the packaging art; and more specifically it is concerned with a flexible package which is utilized primarily to store, contain and dispense a plurality of individual flexible bags.

Flexible packages as for use in the home or the like are coming into common usage. Such packages are often stored in flat alignment in a rigid container. This, of course, presents many and varied problems.

For example, a stack of flexible sandwich bags or the like, when stored within a rigid container, will tend to remain firmly in place so long as the rigid container remains full. As soon as a portion of the flexible bags are removed from the rigid container, the remaining sandwich or the like will tend to move thereabout in a random fashion, destroying their effectiveness for the consumer. This disadvantage is especially significant in that it prohibits flexible packages, when stored in a rigid container, from being fastened to a wall or a rack, or the like, in that the flexible packages will tend to then fall to the bottom of the package, presenting a disorderly appearance.

There have been prior attempts to provide an outer flexible package for sandwich bags or the like. Such prior art attempts have not been successful. Usually the outer flexible package is destroyed when the package is first opened, thereby preventing its effective use thereafter. Additionally, more complicated outer flexible packages, such as those incorporating a snap closure, although capable of reuse, make difficult the removal of the flexible packages stored therewithin.

It is a cardinal object of this invention, therefore, to provide an outer flexible package for bags to be stored therewithin, as for example, sandwich bags and the like for the home consumer.

Another primary object of this invention is the provision of a flexible container as described that will be efficient and that will be economical to mass produce.

Yet another function and purpose of this invention is to provide an outer flexible package as above-described, with an easy opening access arrangement whereby one or more of the bags stored therewithin may be removed without disturbing the remainder of the said bags.

An ancillary object and accomplishment of the invention described herein is the provision of a flexible outer package for sandwich bags or the like that will prevent the inadvertent or spontaneous removal of one or more of the bags stored therewithin prior to sale to the ultimate consumer.

Yet another function and object hereof is the provision of means to automatically indicate to the consumer that there are only a few inner bags remaining in the package, and that it is, therefore, time to purchase an additional package.

With the above objects in view, the invention consists of the following specific arrangement of parts as set forth in detail in the following specification and referred to in the attached drawing, in which:

FIG. 1 is a front elevational view of one embodiment of the instant invention.

FIG. 2 is a sectional elevational view taken substantially vertically through the center of the device illustrated in FIG. 1.

FIG. 3 is a view on a reduced scale corresponding to FIG. 1 showing one of the inner sandwich containers or the like being removed.

2

FIG. 4 is an end elevational view of a stack of bags fabricated according to one embodiment of this invention prior to filling and sealing.

FIG. 5 is a view corresponding to FIG. 4 but showing 5 an alternate embodiment of this invention.

FIG. 6 is a view corresponding to FIG. 4 but showing another alternate embodiment of this invention.

Referring to the drawings and especially to FIGS. 1 and 2 thereof, there is shown a typical working embodiment of this invention.

In the illustrated embodiment, the package consists of a package portion and a header or hang portion 11. The header portion 11 consists of a passage 11a and may contain a reinforcing strip 12a or the like, if desired. The reinforcing strip 12a insures that the package is maintained in a flattened and non-wrinkled condition even when the package is supported as from a rack or the like (not illustrated). In an optional embodiment of the invention a center grommet 45 is positioned at a suitable position along the header position 11 of the package 10. The grommet 45 or other reinforcing structure will serve to prevent the bag from being prematurely torn although suspended from a rack.

The major portion of the container 10 will consist of 25 overlying front 42 and rear 43 walls heat sealed together along their edges as will be explained in detail hereinafter. A first heat seal line 22 will serve to separate the body portion of the package 10 from the header passage 11. The front and back walls 42, 43 will further be sealed together 30 at their opposite vertical edges 24 and 25 as illustrated leaving only the bottom of the container open for filling as will be set forth.

Referring now to FIG. 4 of the drawings, the use of the container 10 is illustrated.

35 It may be seen that the lower wall 43 of the package 10 is somewhat longer than the opposite wall 42 thereby providing an extending flap 12.

Referring again to FIG. 4, the bags 70 will be stacked in uniform and vertical alignment so that a projecting 40 prong 19 will extend through each of a set of aligned apertures 18a through the lips 18. Thus, the prongs 19 serve to insure that the stack of bags 10 are held together until ready for use and filled.

Again, as will be observed in FIG. 4, a nozzle 20 for 45 air or the like is suitably provided to blow into the uppermost bag 70. This will billow open the said top bag 70 preparing the same for filling. The operator will then insert a predetermined number of sandwich bags or the like within the interior of the package 10 between the walls 42 and 43 as seen in FIG. 2. After the bags are 50 securely inserted therewithin, a heat seal knife or the like will descend through the opposite walls 42 and 43 together with the inverted portion 12 extending from one of the walls 43. The heat seal knife in this embodiment 55 will seal together the three layers 42, 43 and 12 and sever the lower and lip portions, thereby forming a fully enclosed package.

Referring again to FIG. 1 of the drawings, one or more 60 lines of perforations 16 are provided about three sides of the inverted portion 12. The top side 12b of inverted portion 12 is already open. Thus, when desired, for ultimate use, the inverted portion 12 may be grasped at the top edge 12b and pulled away from the remainder of the package and torn along the multiple lines of perforations.

65 As will be seen in FIG. 3 and in FIG. 1, a cross line of perforations or other weakened tear lines 60 and 61 are provided in the wall of the package 42 directly under the inverted portion 12. The cross lines 60 and 61 are for the quick removal of the plurality of sandwich bags 70 or the like stored within. However, access to the cross weakened lines 60 and 61 may not be gained until the

inverted portion 12 overlying the lines 60 and 61 are removed.

This, of course, acts as a safeguard to prevent the inadvertent or spontaneous removal of some of the stored bags 70 prior to the sale to the ultimate consumer as in a supermarket.

Once the inverted portion 12 is torn off along lines 16 and the cross weakened lines 60 and 61 are perforated as desired, one of the stored bags 70 at a time is removed from the interior of the package 10 merely by urging the said bag 70 through the opening 40 caused by the weakened lines 60 and 61.

An alternate embodiment of this invention is shown in FIG. 5.

That embodiment of the invention is substantially similar to that described above, except the inverted lip portion 12d is bent under and, therefore, lies between walls 42a and 43a. Thus, the inverted portion 12d prevents the removal of bags from within the interior of the container 10a even after the weakened lines 60 and 61 are perforated, and until the inverted portion 12d is similarly torn off along lines of perforations and removed through the cross sealed openings 40. As the inverted lip portion 12d will usually have extensive advertising matter thereon, it will be obvious to a storekeeper or the like if the package is prematurely opened.

Still another embodiment of the invention is shown in FIG. 6 of the drawings. In this embodiment, the inverted lip portion 12e is replaced by a separate strip overlying one of the walls 42b in such a manner as to cover the provided tear lines 60 and 61. It will be observed that this will make unnecessary the provision of a line of perforations at the bottom of the attachment of the strip 12e as the said strip 12e is not joined to either of the opposite walls 42b or 43b. Additionally, in this embodiment of the invention the said strip 12e is not integrally joined to the opposite edges of the said bag 10b. A layer of prepared material such as shellac or the like is imprinted on the underside of the strip 12e in the area where the said strip 12e is eventually to be severed and sealed. The resulting heat seal between the strip 12e and the edges of the walls 42b and 43b is not strong and is relatively easy to tear or destroy.

Thus, this embodiment of the invention is as described hereinabove.

The strip 12e will overlie the weakened lines 60 and 61 and will prevent the premature removal of the flexible packages 70 stored within prior to the tearing off of the said strip 12e. The said strip 12e may be relatively easily torn off in view of the weakened heatseal lines at their point of juncture with the side edges of the bag as described.

As was mentioned heretofore, in all cases, the lip portion of the bag overlying the weakened lines will contain suitable advertising matter, premium information, or instructions thereof so that should the said strip be prematurely removed, the ultimate consumer will be warned that one or more of the flexible packages stored therewith may be missing.

Additionally, as demonstrated in FIG. 3 of the drawings, a suitable marking, possibly in the form of a bullseye 41 may be provided at the back surface 43 of the package 10, or imprinted on a cardboard reinforcing strip inserted therewith. As the flexible sandwich bags 70 to be stored therewith are usually somewhat transparent, the appearance of the bullseye bags or other marking may be utilized as a warning that enough of the stored bags within have been removed to warrant purchase of a new and replacement stack.

An especially important feature of this invention is the use of a flexible outer container to store flexible bags therewith. As was mentioned hereinabove, the use of

rigid containers for this purpose has been found to be entirely unsatisfactory. This is because the rigid outer containers will not collapse as the stored bags are removed and thus will permit the stored bags to fall into disarrangement after some of the said bags are utilized. In the instant invention, however, the mere weight of the package will tend to collapse the opposite walls 42 and 43 against the bag 70 stored therewithin, no matter how many of the said bags 70 have been removed. Thus, the bags 70 will remain in alignment, which is both pleasing and uniform, until all of the said bags 70 have been utilized for their desired purpose.

Still further the use of the various embodiments of the inverted strip of material or the separate band overlying the weakened lines for removal of the interior bags, should not be overlooked. This inverted or separate portion of material can easily be utilized for special messages, advertising, premium information, and the like in addition to its designated use as a safety protector for the interior of the package.

While there are above described but a limited number of embodiments of the product of this invention, it is to be realized that still other embodiments may be possible within the scope thereof. For example, additional materials may be utilized and many techniques may be utilized for the desired heat sealing and severing purposes, as well as to retain the formed outer packages 10 in their aligned relationship. Still further, various techniques may be utilized to insure that the strip covering the tear lines may be easily removed, when desired.

Having thus described my invention and illustrated its use, what I claim as new and desire to secure by Letters Patent is:

1. A storing and dispensing package, comprising:
  - (a) front and rear overlying walls of flexible material joined together at their marginal edges,
  - (b) a heat seal line joining said overlying walls adjacent one of said marginal edges forming an interior passage between said heat seal line and said marginal edge,
  - (c) and a central area of said front wall provided with lines of perforations whereby said front wall may be torn open at said central area,
  - (d) and a band of flexible material overlying said side of said front wall away from said rear wall covering said central area of said front wall provided with perforations,
  - (e) said band being joined to at least two of said marginal edges along perforated lines, whereby said band may be torn from said front wall along said line of perforations when said package is to be opened.
2. A storing and dispensing package as set forth in claim 1 wherein the marginal edge of said walls opposite said interior passage is open in the initially manufactured position for ease of filling.
3. A storing and dispensing package as set forth in claim 1 wherein said front wall perforations are in the form of a pair of crossed lines.
